UNITED STATES PATENT OFFICE.

HENRY W. HILLE, OF NEW ORLEANS, LOUISIANA, ASSIGNOR TO LEON LAVEDAN, OF NEW ORLEANS, LOUISIANA.

SUBMARINE TORPEDO-DISCHARGING DEVICE.

1,174,723.

Specification of Letters Patent.

Patented Mar. 7, 1916.

Application filed April 16, 1915. Serial No. 21,652.

To all whom it may concern:

Be it known that I, HENRY W. HILLE, a citizen of the United States, and a resident of New Orleans, in the parish of Orleans and State of Louisiana, have invented certain new and useful Improvements in Submarine Torpedo-Discharging Devices, of which the following is a specification.

This invention relates to an improved device for discharging torpedoes or bombs from submarines, and one of the principal objects of the invention is to provide a means whereby a torpedo or bomb may be discharged when the submarine moves into close proximity with its target, so that there will be no danger of the torpedo or bomb missing its objective.

Another object of the invention is to provide a device of the class described in the nature of a tube or cylinder connected with a submarine boat, and adapted to receive a magnetic bomb, a mechanism being provided and being operable from within the boat whereby to eject the bomb from the tube when the submarine is in advantageous position relatively to its objective, so that the bomb may be accurately placed.

Still another object is to provide a torpedo or bomb discharging means in which a cylinder or tube for the reception of the bomb is provided, and a mechanically operable piston is provided for ejecting the bomb from the cylinder, the piston and bomb being detachably connected together by means of a lug whose function it is to detachably connect the bomb with the piston, the action of the lug being such as to allow disconnection of the bomb and piston when the latter moves outwardly in discharging the bomb.

A further object of the invention is to provide an improved torpedo discharging means of such nature that a torpedo may be readily inserted within the tube from within the submarine and while the same is submerged.

A still further object is to provide a submarine boat with a blind feeler adapted to project forwardly of the boat and to sound an alarm within the submarine upon coming in contact with a metallic surface such as the hull of a vessel.

As a further object, the provision of a

device of the type described which will be extremely simple, durable, efficient in operation, and inexpensive to manufacture is contemplated.

With these and other objects in view which will become apparent as the description proceeds, the invention resides in the construction, combination, and arrangement of parts hereinafter more fully described and claimed, and illustrated in the accompanying drawings in which like characters of reference indicate like parts throughout the several figures, of which—

Figure 1 represents a view in perspective, partially in section, showing a submarine having a discharging device constructed according to my invention, the submarine being submerged, and having its tube loaded with a bomb or torpedo. Fig. 2 represents a view in section, taken vertically and longitudinally through the forward part of a submarine, showing the tube as being open and the bomb as being disposed upon the jack table. Fig. 3 represents a view in section, partially in elevation, taken on a plane to one side of the tube, and showing the latter as in closed position. Fig. 4 represents a plan view of Fig. 3. Fig. 5 represents a detail view in perspective of the closure hood or cap, looking at the same from the inside thereof. Fig. 6 represents a view in perspective, illustrating the method of use of a modified form of the device. Fig. 7 represents a view in section, taken vertically and longitudinally through the front portion of a submarine, showing a modified form of the invention. Fig. 8 represents a view in section, illustrating the manner of inserting the bomb within the tube of the modified form. Fig. 9 represents a fragmentary view in elevation taken from the front of the tube or cylinder, and showing the disposition of the groove therein. Fig. 10 represents a view in section, taken on the plane indicated by the line 10—10 of Fig. 7. Fig. 11 represents a view in section taken on the plane indicated by the line 11—11 of Fig. 2, disclosing the reel and pneumatic connections for the pneumatic feeler. Fig. 12 represents a view in section, taken through the end of the feeler, showing the arrangement of the casing and electro-

magnet. Fig. 13 represents a diagrammatical view showing the alarm bell and magnet circuits, the lines indicating the wires being extended to connect with Fig. 12 in such 5 manner as to represent the complete circuits. Referring more particularly to the drawings, a submarine boat of suitable type is indicated generally by the letter A. Arranged preferably at the prow of the submarine, and suitably built in and connected with the walls of the boat, is the torpedo or bomb discharging tube or cylinder 7. The latter in the form indicated in Figs. 1, 2, 3, and 4, is preferably inclined upwardly 10 toward its outer end. The tube is open at both ends, and at its inner end is defined by an annular flange 35 which is interiorly threaded as at 36. A breech block 37 exteriorly threaded as at 38 for engagement with the threads 36, is provided. The breech block is provided with a marginal flange 39 for engagement with flange 35 when the block is screwed home. Said block is equipped with a ring 40 to provide 15 a hand hold whereby the block may be turned into position. A round piston stem 41 slidably extends through a stuffing box 42 provided on the breech block, and is connected at its forward end in advance of 20 said breech block with a piston 10. The latter is adapted to be slidably disposed within the tube 7, and to be reciprocated therein through the action of stem 41 whereby to discharge a bomb or torpedo from the 25 tube at will. The stem 41 at its rear end is connected through the medium of a universal joint 43 with a rack bar 44. The latter is adapted to be operated through the medium of a sprocket wheel 14 carried on 30 a shaft journaled in a bracket 15, which is suitably secured to the floor of the boat. The sprocket 14 is operable by means of the foot pedal 16, adapted to be actuated by the feet of the operator of the boat. As 35 indicated in Fig. 1, when the breech block is out of engagement with the flange 35, the rack bar is in a rearwardly shifted position, and does not engage with the sprocket 14. However, when the breech block is moved 40 forwardly into engagement with the rear end of the tube, the rack bar is shifted forwardly and engages with the sprocket wheel in such position as to be operated by the latter in order to reciprocate the piston 45 within the tube.

A substantially U-shaped yoke 45, which is pivoted in a bracket 46, is utilized in supporting the rack bar when the latter is out of engagement with the sprocket wheel. 50 When in engagement with the sprocket, the rack bar is prevented from accidentally kicking or jumping off of the same, through the medium of an idler pulley, or roller 47, indicated in Fig. 1 as being carried by a 55 suitable spring controlled arm 48 in such

manner as to be rested at will upon the top side of the rack for holding the latter in engagement with the sprocket.

The embodiment of the device indicated in Figs. 1 and 2 provides a torpedo tube 70 adapted to be loaded from within the submarine, and either while the latter is at the surface or is submerged. On the other hand, the type indicated in Figs. 6 and 7 is such as is adapted to be loaded only from without the submarine, and while the latter is at or near the surface. In the arrangement indicated in Figs. 6 and 7, the prow of the submarine is provided with a flat circular portion 5 defined by an annular outwardly 75 extending flange 6. Portion 5 is adapted to form the inner wall or breech of the bomb receiving cylinder or tube, indicated at 7a. The tube at its inner end is provided with an outwardly extending annular flange 8 80 adapted to be connected to flange 6 through the medium of suitable fastening means, such as bolts 9. In both forms, the tube or cylinder is preferably made of aluminum or some other non-magnetic substance. The 85 modified form of tube, in common with the preferred form, is provided with a piston 10 operable through the medium of a piston stem 11 extending through a stuffing box 12 provided on the annular flat portion 5. 90 The piston stem 11 projects within the submarine and at its inner end is provided with a rack bar 13 forming a prolongation of the stem, and fixed with relation to said stem. This rack bar is adapted to be operated by 95 means of a sprocket mechanism as already described.

Both forms of the discharging tube are adapted preferably to be used in connection with a magnetic bomb or torpedo indicated 100 at B. The latter is substantially cylindrical in shape, and is adapted to fit snugly within the chamber or tube. This bomb is provided with a number of electrically connected batteries or cells 17 forming a source 110 of current. The latter is connected at one end or pole with the contact leaf 18 and at its opposite pole with a similar contact leaf 19. A plurality of electrically connected electro-magnets 20 are arranged in the fore 115 part of the bomb, and are connected by means of a contact leaf 21 with the contact leaf 18. The opposite terminal of the magnet is in the form of a contact leaf 22. The leaves 19 and 22 are normally maintained 120 out of engagement with each other when the bomb is in the chamber, by means of a pin 23 extending through the wall of the bomb and controlled by the spring 24. This pin is preferably made of some non-conducting material.

The lower portion of cylinder or tube 7 in the modified form, is provided interiorly and longitudinally and near its outer end, with a channel or groove 25 having a stepped 130

floor 26. The normal tendency of the spring 24 is to shift the pin 23 outwardly, relatively to the contacts 19 and 22, so as to allow the closing of these contacts and the 5 completion of an electric circuit through the magnets 20 for energizing the latter. In placing the bomb within the tube 7 from the outside thereof, the inner end of the pin 28 is arranged in alignment with the 10 groove 25, so as to ride within the same and to engage against the stepped floor 26 whereby, as indicated in Fig. 7, when the bomb is in finally retracted position, the pin is forced through the action of the steps 15 in the floor, in between the contacts 19 and 22 so that the circuit through the magnets will remain open until the bomb is discharged. At that time the spring 24 will withdraw 20 the pin and allow the completion of the circuit so as to energize the magnets.

When the bomb or torpedo is to be inserted within the tube 7 in the modified form, the piston 10 is moved toward the outer end of said tube to attain the position 25 indicated in Fig. 8. The bomb is then partially inserted within the outer end of the tube into engagement with the piston, and the lug 27 is then disposed within the groove 25 in the position indicated in Fig. 8. This 30 lug is provided at its inner end with a substantially rectangular tooth 28, and at its outer end with a wedge shaped tooth 29. The teeth 28 and 29 are adapted to engage in similarly shaped notches 30 and 31 respectively provided in the piston 10 and bomb B. The recess 30 is provided in the periphery of the piston at the lowest point thereof, and the recess 31 is provided in the bomb near the inner end thereof and in 35 alignment with the point at which the pin 23 is disposed. This lug 27, it will be noted, is so disposed when the bomb is being inserted within the tube or cylinder, as to lie in an inclined position against two of the 40 steps in the floor of the groove 25, as indicated in Fig. 3. When in this position, the lug or tooth 28 engages partially within the recess 30. When the parts are in this position, the piston 10 is withdrawn into the 45 inner end of the chamber, and as the lug 27 is carried with it, it moves from one step in the floor of the groove into the next higher step and thus engages within the recess 31. Hence, as the piston is withdrawn, the lug 50 acts as a medium for connecting the piston and bomb so that the bomb will be withdrawn into the proper position within the tube or cylinder.

When the bomb is discharged through 55 the outward movement of the piston 10, the lug 27 as it reaches the outer end of the recess 25, drops down and thus disengages the piston and bomb or torpedo, whereby to allow the latter to remain in engagement 60 with the side or bottom of a vessel as indi-

cated in Fig. 6, through the action of the magnets 20, which as already set out, are automatically thrown into circuit with the batteries when the bomb or torpedo is discharged. This lug is thus lost when the 70 bomb or torpedo is completely discharged, but should it be found by the operator that after partially discharging the bomb, it would be more advantageous to discharge it at a different point, he may, by withdrawing 75 the piston, withdraw the bomb again into the cylinder. However, the bomb must be withdrawn before it has been discharged or moved outwardly too far in the cylinder, otherwise the lug will completely disengage 80 itself from the piston and bomb and thus prevent withdrawal of the latter.

The bomb or torpedo is controlled by a time mechanism indicated generally at C. The latter is actuated through the medium 85 of a key 32 which projects centrally from the rear end of the bomb or torpedo. In order to maintain this key against rotation, and thus prevent unwinding of the time mechanism while the bomb is in place with 90 in the tube, the piston 10 is provided centrally in its front face with a slot or elongated recess 33 within which the key 32 is retained. However, as soon as the bomb is discharged, the key is thus released, and the 95 time mechanism which has previously been set to allow the elapse of any desired space of time before the explosion of the bomb, commences running.

As indicated in Fig. 6, the method of 100 using the modified form is to drive the submarine to a point in close proximity with the ship or other object of attack, and then by working the foot operable mechanism, move the piston outwardly whereby to discharge the bomb and allow the same to adhere to the bottom of the vessel through the action of magnetism. The time mechanism of course will be set to allow time enough 105 for the submarine to move out of range before the explosion occurs.

In the preferred form, as indicated in Figs. 1 and 2, the tube or cylinder is provided with an interior longitudinally extending groove or channel 49 running its 115 entire length and having deepened portions 50 at its front and rear ends adjacent the ends of the tube or chamber. This channel or groove is for the reception of the pin 23 and lug 27. In the preferred form the 120 connection between the bomb and piston through the medium of the lug 27 is formed in the same manner as that already described, the piston and bomb being provided with the recesses for the reception of the 125 teeth on the lug.

When the tube is of the breech loading type, as indicated in the preferred form, the submarine is provided with a suitable foot operable jack 51 arranged adjacent the 130

breech of the tube and provided with an inclined jack table 52 which may be raised at will into the position shown so as to support the bomb as the latter is being inserted within the tube. When the bomb is far enough within the tube to be maintained in place by the latter, the jack table may be lowered. This table is provided with a longitudinally extending groove 53 for the reception of the head of pin 23. The groove is enlarged transversely at its upper portion as at 54 for the reception of the lug 27.

In the modified form of tube, means is provided whereby the outer end of the tube 15 may be hermetically sealed at will, in order that the tube may be loaded with a bomb or torpedo, while the vessel is submerged. This apparatus includes a hood, or closure, or cap indicated at 55. This closure is longitudinally and transversely concaved, and tapers toward its ends, being substantially in the form of a lune or spherical sector. The closure or hood is mounted for oscillation upon the pins 56, which extend laterally from the 25 outer surfaces of tube 7 at diametrically opposed points. These pins project through slots or elongated recesses 57 provided adjacent the ends of the closure 55. By swinging the closure upwardly and downwardly 30 upon the pins 56 as pivots, the tube is respectively closed and opened. In order to accommodate the curvature of the closure, the sides of the tube near its outer end, are beveled as at 58. This closure on its inner 35 surface is provided with a compressible strip or washer or packing 59 adapted to engage upon the tube 7 at the outer end of the latter for forming a water tight joint between the closure and tube in a manner to be hereinafter more fully described.

In order that the closure may readily be actuated from within the submarine, a mechanism is provided which includes a rack bar 60 extending through a stuffing box 45 61 for longitudinal reciprocation within the latter, the outer end of this rack bar being connected by a link 62 having a broken joint at 63, with an ear 64 provided on the closure 55 at one end thereof and between the adjacent pivot point of the closure and the wall of the submarine. Carried by a bracket 65 within the boat, is a pinion wheel 66 operable through the medium of a crank arm 67 for driving the rack bar 60 in one direction 50 or another, it being understood that by turning the crank 67 in one direction, the rack bar will be shifted outwardly whereby to open or depress the closure 55, and by turning the crank arm in the opposite direction, the rack bar will be withdrawn for raising the closure. A spring actuated dog 68 is carried by bracket 65 and is normally in contact with the pinion 66 to prevent rotation of the latter. This dog is kicked 60 or moved out of engagement with the pinion

when the rack bar is to be shifted for operating the closure.

Arranged on each side of the tube and extending each through a stuffing box 69 is a rod 70. The outer end of each rod is connected by means of a link 71 with one end of the closure or hood 55. The inner end of each rod 70 has a pin and slot connection 72 with a lever 73 pivoted upon a bracket 74 supported within the vessel. 75

The mechanism just described is designed for the purpose of drawing the hood or closure 55 bodily against the outer end of tube 7, whereby to compress the washer or packing 59 against said tube in order to 80 form a water tight joint. Each of the levers 73 carries a dog 75 adapted to coact with a toothed segment 76 in maintaining the lever in adjusted position. A lever mechanism is provided for each end of the closure or cap 85 55, in order that the tension on each side of the closure may be regulated.

It will be understood that when the tube is to be loaded while the vessel is submerged, the closure will be shifted into the position 90 indicated in Figs. 1, 3, and 4, for sealing the outer end of the tube. The breech block may then be disconnected and shifted rearwardly and the bomb disposed upon the jack table and shifted into the breech of the tube, 95 whereupon the breech block may be turned home so as to seal the inner end of said tube. The dogs 75 may then be kicked out of engagement with the segments 76, and the tension upon the closure thus relaxed, and at 100 the same time the rack bar 60 may be shoved outwardly whereby to swing the hood downwardly into the position shown in Fig. 2, thus unclosing the outer end of the tube. 105

A stop lug 77 is provided on the outer surface of the vessel, and is adapted to limit the downward movement of closure 55. Upon the upper surface of tube 7 adjacent the outer end of the latter, is disposed a bumper 110 in the form of a pneumatic or other compressible member indicated at 78. This bumper while acting as a stop for the upward movement of the hood, also prevents engagement of the outer end of the tube with the hull of 115 a vessel or other object, whereby damage to the tube will be prevented.

In order that the occupants of the submarine may be informed when the submarine is in close proximity to a vessel or other object, I have provided a mechanism in the nature of what I term a "blind feeler." This device includes a flexible tube 79 extending at its inner end, as indicated in Fig. 11, through an opening 80 in a casing 120 81 carried on the outside of the submarine, said tube 79 having a suitable connection with a hollow shaft 82 of a reel. This shaft is journaled within the housing or casing 81, and at its outer end 83 has a swivel connec- 125 130

tion with one end of a curved pipe 84, whose opposite end is suitably connected with an air supply pipe 85 leading from a suitable tank or other compressed air supply. The 5 inner end of shaft 82 is provided with a handle 86 whereby the tube 79 may be wound upon the shaft when said tube is deflated. A valve 87 in the line 85 as indicated in Fig. 2, is adapted to control admission 10 of air to the flexible tube 79. By closing the valve 87 and opening the relief valve indicated at 88, the tube may be deflated at will, in order that it may be wound upon the reel. Arranged at the other end of the tube 15 79 is a casing 89 of suitable material. Slidably disposed within this casing is an electro-magnet 90. The terminals of the coil of the magnet are connected through the medium of the wires 91 and 92 respectively, with the opposite poles of a storage 20 battery indicated at 93 in Fig. 13, which battery may be utilized to furnish current for the motor for driving the submarine. Upon the other end of the magnet, and insulated from each other, are a pair of contacts 94 and 95. Each of these contacts is in 25 electrical communication with one pole of a battery or other suitable source of electrical current 96, through the medium of the wires 97 and 98 respectively. In one of the lines 97 and 98, an alarm bell 99 is arranged. This bell is disposed within the submarine in a suitable position to be heard by the operator of the vessel, when the bell 30 is rung. At the other end of casing 89 and in alinement with the contacts 94 and 95, are arranged the contacts 100 and 101 respectively. The latter are in communication with each other through the medium 35 of an electrical conductor 102. As the tube 79 is inflated in extending the same, it carries with it the casing 89 within which the electro-magnet is disposed. This casing as noted in Figs. 1 and 2, is arranged at the 40 outer end of the tubing, and when the latter is entirely inflated, it is disposed in such relation with the submarine as to sway about in the water in advance of the latter, so as to come in contact with any object 45 such as the hull of a vessel, before contact of the submarine with that object. Or, if the submarine has been submerged in the path of a vessel, the latter will, upon coming close to the submarine, engage against the 50 casing 89. Upon movement of the casing into proximity with a metallic surface, such as the hull of a vessel, the magnet 90 will be attracted toward the outer end of the casing, against the tension of a coiled spring 55 103 arranged between the electro magnet and the casing end. This movement of the magnet will shift the contacts 94 and 95 into engagement with the contacts 100 and 101, and a circuit will thus be established 60 through the wires 97, bell 99, battery 96, and electrical conductor 102, thus ringing the bell and indicating to the occupants of the submarine that the submarine is in close proximity to a vessel. At this time the bomb may be discharged, and will, through 70 the action of the magnets carried by it, move into engagement with and adhere to the side of the oncoming vessel. The length of the tube or feeler 79 is such that when the alarm is sounded, the occupants of the submarine will know that they are close enough 75 to their objective, to discharge the bomb. The magnet and bell wires are carried within tube 79 by means of a suitable conduit 80 104. This conduit extends at its inner end through the outer end of shaft 82 and through the pipe 84, and from thence through a pipe 105 to the batteries. A suitable connection will of course be provided between the pipe 105 and the pipe 85, to 85 prevent entrance of air from last said pipe into the pipe 105. As soon as the submarine and the object of attack move apart, the electro-magnet will be shifted into position 90 at the rear end of the tube through the action of spring 103, thus breaking the bell circuit and silencing the bell.

In the preferred form, the tube or cylinder 7 is provided with a drain pipe 106 communicating at its upper end with the 95 tube at the rear end of the latter, and at its lower end communicating with a suitable chamber, this pipe being provided with a valve 107 for controlling the drain. By means of the pipe, the water inclosed within the tube after discharge of the bomb and after the hood has been raised into closing position, may be drained from the tube before the breech block is removed, incident to the placing of another bomb within the 100 tube.

Although I have described the preferred embodiment of my invention, I may desire to make such changes in the construction, combination, and arrangement of parts 110 thereof, as do not depart from the spirit of the invention and the scope of the appended claims.

I claim:

1. The combination of a submarine vessel, 115 a tube associated therewith and extending outwardly therefrom, a breech block adapted to be removably connected with the inner end of the tube from within the submarine, a piston stem slidably extending through said breech block, a piston carried by the stem in advance of the block and adapted to be reciprocated within the tube, a manually actuatable means for operating the stem whereby to reciprocate the piston at will, 120 said tube being adapted to receive an electrically controlled magnetic bomb, a lug adapted to detachably connect the piston and bomb together and adapted when the latter is ejected to become detached from 125 130

- 5 said piston and bomb, said bomb being provided with means whereby to render the bomb demagnetized while within the cylinder, said cylinder being provided with a 10 channel for the reception of the demagnetizing means and the lug, and means for closing the outer end of the tube at will whereby to exclude water from the tube when the submarine is submerged.
- 10 2. The combination of a submarine vessel, a tube associated therewith and adapted to receive a bomb, a breech block adapted to be detachably connected with the tube from within the submarine for closing the inner 15 end of said tube, a piston stem slidably extending through the breech block, a piston fixedly connected with the stem in advance of the block and adapted to be reciprocated within the tube, manually operable means 20 for moving the stem in one direction and another, means for detachably connecting the piston and bomb while the latter is within the tube, said means adapted to disconnect them upon ejection of the bomb, 25 said tube being provided with a groove for the reception of the said connecting means and for the reception of a means for demagnetizing the bomb while the latter is within the tube.
- 30 3. The combination of a submarine boat, a tube associated therewith and extending outwardly therefrom, a breech block adapted to be connected with the tube for closing the inner end of said tube, a stem slidably 35 extending through said breech block, a piston carried by the stem in advance of said block and adapted to be reciprocated within the tube through operation of said stem, a jack, and a table associated with 40 said jack and adapted to be moved into proximity with the rear end of the tube at will, for supporting a bomb while the latter is being placed within the tube, said jack table and tube being provided with a channel 45 way for receiving a bomb carried means for demagnetizing the bomb while within the tube, substantially as described.
4. The combination of a submarine boat, a tube associated therewith and extending 50 outwardly therefrom, a breech block adapted to be detachably connected with the tube for closing the inner end of the latter at will, means adapted to be reciprocated within the tube for ejecting a bomb therefrom 55 at will, means slidably extending through said breech block for operating said first means, and means whereby said second means may be operated at will.
5. In a device of the class described, a 60 submarine, a tube associated therewith and extending outwardly therefrom, said tube adapted to receive a bomb, a hood associated with the tube and having a pin and slot connection therewith, said hood adapted to 65 be moved into positions for closing and for opening the outer end of the tube, a compressible washer carried by the hood and adapted to be compressed between the same and the outer end of the tube, an ear carried by the hood adjacent one of the pin 70 and slot connections, means operable from within the submarine and connected to said ear for swinging the hood into opening and closing positions, and means operable from within the submarine and connected to the 75 hood and adapted to shift the latter bodily toward the tube when in closed position for compressing the washer between said hood and tube.
6. The combination of a submarine vessel, 80 a tube associated therewith and adapted to receive a bomb, means whereby the inner end of the tube may be opened and closed at will, means whereby a bomb may be ejected from the tube at will, a hood associated with the tube and having a pin and slot connection therewith and adapted to be shifted for closing and for opening the outer end of the tube, means operable from within the submarine whereby the hood may 85 be moved into closing and opening positions, means operable from within the submarine whereby the hood may be shifted bodily toward the tube when in closed position, and means adapted to be compressed 90 between the hood and tube when said hood is so shifted, whereby to form a watertight joint between the hood and tube.
7. A device of the class described, including a tube adapted to receive a bomb, a hood 100 associated with said tube and adapted to be shifted relatively thereto for closing and for opening the outer end of the tube, means for limiting the opening movement of the hood, and a bumper carried by the tube for 105 preventing contact of said tube with foreign obstacles, said bumper adapted to limit the closing movement of the hood.
8. The combination of a submarine, a tube associated therewith, a hood provided with 110 ends embracing the tube between them and having a pivotal and a sliding connection with the tube, means whereby the hood may be swung upon its pivot for closing and opening the tube at will, and means whereby the hood may be shifted bodily relatively 115 to the tube for forming a tight connection therewith.
9. The combination with a submarine torpedo tube, of a hood provided with ends extending alongside the tube and having a pin and slot connection with the tube, said hood adapted to be swung upon its pivot for closing and opening the tube at will, and adapted further to be shifted bodily relatively 120 to the tube for forming a tight connection therewith.
10. The combination of a submarine, a reel associated therewith, a flexible tube connected with the reel and disposed without 125 130

the submarine, means whereby the tube may be inflated and deflated at will, a casing carried by the tube at the outer end thereof, an electromagnet associated with the casing, 5 means whereby the electromagnet may be energized, and an alarm circuit adapted to be closed upon movement of the electro-magnet outwardly with respect to the casing whereby to sound an alarm within the submarine upon movement of the casing into 10 close proximity with a metallic object.

11. In a device of the class described, the combination with a submarine boat, of a flexible tube adapted to be inflated and deflated at will, and being provided with means whereby an alarm within the submarine may be sounded upon movement of the outer end of the tube into close proximity with a metallic object.

12. The combination of a submarine, a tube associated therewith and adapted to receive a magnetic bomb, means whereby the bomb may be ejected from the tube at will, a flexible tube associated with the submarine 20 and adapted to be inflated and deflated at will, and means associated with the flexible tube and adapted to be actuated for sounding an alarm within the submarine, upon movement of the flexible tube into close 25 proximity with a metallic object, whereby to notify the occupants of the submarine of the proper time to eject the magnetic bomb.

13. The combination with a submarine, of a tube adapted to receive a magnetic bomb, 30 means whereby the bomb may be manually ejected at will, and means associated with the submarine for sounding an alarm within the same when the submarine is in proper position relatively to its objective for ejecting the bomb.

14. The combination of a submarine vessel, a tube associated therewith, a piston operably disposed within the tube and adapted to be actuated from within the submarine, 45 said tube adapted to receive an electrically controlled magnetic bomb in such manner as to render the bomb demagnetized while within the tube, means for detachably connecting the bomb and piston while the former is within the tube and adapted when 50 the bomb is ejected to become disconnected from said bomb and piston, and means associated with the piston for rendering a time mechanism carried by the bomb inactive 55 while said bomb is within the tube.

15. The combination of a submarine vessel, a tube associated therewith and adapted to receive a magnetic bomb, means operable from within the submarine whereby the 60 bomb may be ejected from the tube at will, means whereby a time mechanism carried by the bomb may be rendered inactive while the bomb is within the tube, and means asso-

ciated with the tube whereby a pin carried by the bomb may be positioned for demagnetizing said bomb while within said tube. 65

16. The combination of a submarine having a bomb receiving means and being provided with a mechanism for ejecting the bomb at will, a connecting means between the bomb and ejecting mechanism for maintaining them together while the bomb is within the receiving means and adapted to disconnect the bomb and ejecting means upon ejection of the bomb. 75

17. In a device of the class described, the combination with a submarine, of a bomb receiving means, means operable from within the submarine at will for ejecting a bomb from the bomb receiving means, means associated with the ejecting means for rendering a time mechanism carried by the bomb inactive while within the bomb receiving means, and means for detachably connecting the bomb and ejecting means while the former is within the bomb receiving means, and adapted to disconnect said bomb and ejecting means upon ejection of the bomb. 80

18. The combination with a submarine, of a bomb receiving means, a mechanism operable from within the submarine at will for ejecting a bomb from said receiving means, means associated with the bomb receiving means for rendering the bomb inactive while within the receiving means, and means for 90 detachably connecting the bomb and ejecting means together while the former is within the receiving means and adapted to disconnect them upon ejection of the bomb. 95

19. In a device of the class described, the combination of a tube adapted to receive a bomb, means for ejecting the bomb at will, and means for detachably connecting the bomb and ejecting means together while the former is within the tube and adapted to 100 disconnect them upon ejection of the bomb. 105

20. In a device of the class described, a tube adapted to receive a bomb and being provided with a channel of varied depths, said channel adapted to receive a pin carried by the bomb for rendering the latter inactive while within the cylinder. 110

21. In a device of the class described, the combination with a cylinder adapted to receive a magnetic bomb, of a mechanical device for ejecting the bomb at will, means for detachably connecting the mechanical device and bomb together while the latter is within the cylinder, and means associated with the cylinder for rendering the bomb demagnetized while within the cylinder. 115 120
